UNITED STATES PATENT OFFICE

CHARLES H. SAMPSON, OF ROCHESTER, NEW YORK

PRINTING MACHINE

Application filed August 11, 1928. Serial No. 298,982.

The present invention relates to printing machines, and an object thereof is to improve that type designed for writing on checks and other negotiable instruments. Another object of the invention is to provide an improved platen operating mechanism. Still another object of the invention is to provide a feeding device having a feeding mechanism in which a single ratchet wheel is operated upon by two platen operating mechanisms. A further object of the invention is to provide a platen operating mechanism having a positive and an elastic connection with a member which operates a pawl in the feeding mechanism of the feeding device. Another and further object of the invention is to provide a novel stop for the feeding device through which the latter may be stopped to position the check at the beginning of the date line or at the beginning of the line for the payee's name or the amount. A still further object of the invention is to provide a locking mechanism for the printing member having a resilient connection with the platen operating mechanism so that said locking device will yield with reference to the platen operating mechanism to prevent the breaking of parts in the event that the printing member is not positioned properly with reference to the locking device. Still another object of the invention is to associate with the check writing machine, a dating device of novel construction. Still further and another object of the invention is to provide a novel mounting for the inking means of the printing member of the dating device so that the inking roller travels over the printing device as the latter moves toward its platen.

To these and other ends, the invention consists of certain parts and combinations of parts, all of which will be hereinafter described: the novel features being pointed out in the appended claims.

In the drawings:

Fig. 1 is a plan view of a check writing machine constructed in accordance with this invention;

Fig. 2 is a section on the line 2—2, Fig. 1;

Fig. 3 is a bottom view of the machine with the bottom plate removed;

Fig. 4 is a side view of the machine showing the parts of the feeding mechanism in section;

Fig. 5 is a top view of the machine showing the upper frame member and the feed plate or table removed;

Fig. 6 is a section on the line 6—6, Fig. 1;

Fig. 7 is a section on the line 7—7, Fig. 2;

Fig. 8 is a section on the line 8—8, Fig. 9;

Fig. 9 is a section on the line 9—9, Fig. 8;

Figs. 10 and 11 are two views of one of the platen operating mechanisms, the first showing the platen away from printing position and the second showing the platen in printing position;

Figs. 12 and 13 are two views of the other platen operating mechanism, the former showing the platen away from printing position and the latter showing the platen in printing position;

Fig. 14 is a section on the line 14—14, Fig. 8;

Fig. 15 is a detail top view of portions of the feeding mechanism of the work feeding device;

Fig. 16 is a section on the line 16—16, Fig. 15;

Fig. 17 is a section on the line 17—17, Fig. 15;

Fig. 18 is a section on the line 18—18, Fig. 3;

Fig. 19 is a detail sectional view of the dating mechanism with fragments of the machine;

Fig. 20 is a detail sectional view showing the manner in which the dating mechanism is shifted;

Fig. 21 is a detail view of the frame which carries the dating wheels;

Fig. 22 shows the dating mechanism in printing position;

Fig. 23 is another sectional view of the dating mechanism;

Fig. 24 is a plan view with adjacent parts in section showing the locking device of the check printing member;

Fig. 25 is a side view of the locking device with parts in section;

Fig. 26 is a plan view of the work feed-

ing device showing the manner in which it is guided on its carrier;

Fig. 27 is a section on the line 27-27, Fig. 3;

5 Fig. 28 is a side view of the work feeding device showing parts in section;

Fig. 29 is a section similar to Fig. 27 showing the stop-bar in stop position; and

Fig. 30 is a view of the under side of the feeding device with cooperating parts.

10 In the illustrated embodiment of the invention, the

vention, 1 indicates a base frame of reference.

15 tangential construction having in its rear portion an upwardly and forwardly or over-hanging frame 2. The base frame is closed by a bottom plate 3 secured by a screw anchored at 4 in the corner of two angularly arranged frame pieces 5 and 6. The forward portion of the top of the base frame 1 is closed by a plate 7 secured by screws 8 and serving as the table or work support. A top frame 9 enclosed the overhanging frame 2 and projects over the top plate 7, its rear portion 10 serving to cover the rear 20 portion of the base frame 1 and being secured to the base frame by screws 11. A removable plate 12 serves to cover the bottom of that portion of the upper frame 9 projecting over the top plate 7, being spaced 25 from the top plate 7 to provide a feed passageway for the material to be printed. On the left hand side an opening is provided covered by a removable plate 12^a provided with a pointer or index 12^b which points 30 35 out the printing line of the outer set of printing devices.

40 Mounted to turn on the overhanging portion 2 of the base frame 1 is the printing member comprising, in this instance, a single flat disk 13 having two sets of printing devices of different lengths on the under side thereof like the printing disk shown in the patent to Frederick O. Bullis, No. 1,604,384, granted October 26, 1926. This printing member turns about a vertical axis with its face operating in close proximity to the plate 12. In this instance, the printing member has a vertical shaft 14 turning in the overhanging frame 2 and provided with 45 a gear wheel 14^a at its upper end. This gear wheel has engagement with the teeth of the internal curved rack 15 on an operating member 16 which is mounted to turn on a fixed stub shaft 17 supported on the overhanging frame portion 2 to one side of the shaft 14. An operating arm 18 is secured 50 to this shaft and projects laterally through the upper casing member 9. On this arm is an index or pointer 19 which is adapted 55 to overhang a removable top section 20 of the upper frame member 9. This removable top section 20 has two sets of indications thereon, indicated at 21 and 22, the former for the outer set of single characters, one 60 being visible through an opening 23 in the 65

indicator 19 when at printing position, and the latter 22 for the inner set of longer characters, such as expressions or words, one being pointed out by the end of the indicator 19 when at printing position. 70 The plate 7 has an opening or slot 24 which exposes a single character 21 and one of the words 22 at printing point.

For holding the printing wheel in adjusted position against accidental displacement, there is provided a retaining device comprising, in this instance, a roller 25 mounted to rotate on the lower end of a swinging arm 26 which is pivoted at 27 at its upper end to a bracket 28 secured to the overhanging frame portion 2 (see Fig. 6), and is guided between the roller and the pivot by a slotted guide 28^a on the bracket 28. A spring 29 acts on this arm 26 and holds the latter with yielding pressure toward the periphery of the printing wheel, the latter being notched at 30 opposite each character and expression so as to provide a seat for the periphery of the wheel 25. 75 80 85

Cooperating with the two sets of printing devices on the printing disk, are two platens 31 and 32, the former cooperating with the outer set of printing devices and the latter cooperating with the inner set of printing devices. These platens are mounted below the feed plate 7 and are supported by two levers 33 and 34 respectively, both of which are mounted to turn independently upon a single shaft 35 secured to the base frame 1. The top or work supporting plate 7 is provided with an opening 36 through which the two platens 31 and 32 may be passed in order

to engage with the printing member 13. Operation of the lever 33 (see Figs. 10 and 11) is effected through an operator 37 secured to a rock shaft 38 which has an arm 39 thereon connected by a link 40 to a lever 41 which is mounted to turn on a shaft 42 supported with the shaft 38 by the overhanging portion 2 of the base plate. A link 43 depends from the rear end of the lever 41 and is pivotally connected at its lower end to the rear end of the platen lever 33. Projections 41^a and 41^b are provided on the lever 41 to cooperate respectively with the link 40 and the link 43 to limit the movement of the platen operating mechanism in two directions. A spring 41^c acts on the lever 33 to hold the platen mechanism normally in one position. Movement of the platen carrying lever 34 (see Figs. 12 and 13) is effected by an operator 44 secured to a rock shaft 45 mounted on the overhanging portion 2 of the frame and having an arm 46 connected by a link 47 to the forward end of a lever 48 mounted on the shaft 42 with the lever 41. To the rear end of the lever 48 is pivotally connected a link 49 which in turn is pivotally connected to the rear end of the lever 34. A spring 34^a acts on the lever 34 to hold the platen operating mechanism in normal positon with the forward end of the 130

lever 48 against the arm 46 on the shaft 45. The arc of movement of the operator 44 is limited by an abutment 44^a which abuts a stop 44^b on the overhanging portion 2.

5 With the end in view of locking the printing wheel 13 in printing position and at the same time insuring its being properly centered, the printing wheel has an annular series of upwardly extending spaced projections 50, the upper ends of which are beveled at opposite sides at 51. Arranged to operate between these projections is a detent or dog 52 which turns on a rock shaft 54. This rock shaft also carries an arm 55 to which the detent 52 is resiliently connected by means of a spring 56 (see Figs. 24 and 25). This arrangement permits the descent of the arm 55 without forcing the detent lever 53 downwardly in the event that the detent 52 should engage 10 on the top of one of the projections 50. In other words, there is a yielding connection between the arm 55 and the detent 52. The arm 55 has extending laterally therefrom a pin 56^a which projects in front of the two links 20 43 and 49 (see Figs. 10 to 13) to be engaged by either one of the projections 57 and 58 arranged respectively on the levers 43 and 49. A spring 59 connects the arm 55 with the shaft 42 and serves normally to hold the detent 52 away from the printing wheel 13. With the operation of either one of the controlling members 37 or 44, one of the projections 57 or 58 will engage the projection 56^a and depress the arm 55 against the action of 25 the spring 59. The spring 56 will cause the detent lever 53 to follow and draw the detent 52 between two of the projections 50 on the printing wheel, thus centering such wheel and at the same time holding the wheel 30 against turning during the printing action.

40 With the end in view of supporting the printing wheel adjacent its perimeter over the printing point to take the thrust imposed upon the wheel by the platen, there is provided an abutment 60 which is in the form of an adjustable screw and mounted upon a rigid arm 61 which projects from the overhanging portion 2 of the base frame.

45 Inking of the printing member may be effected by a cone-shaped inking wheel 62 mounted to turn on a bifurcated frame 63 which is securely mounted on a shaft 64 journaled at one end in the shaft 35 in line therewith and having an arm 65 arranged on the exterior of the base frame 1 by which the frame 63 may be moved to swing the roller 62 in cooperation with the two sets of printing devices, the roller 62 dropping out of engagement with the printing devices when the arm 65 is released. This inking roller merely supplies ink to the printing devices. The distribution of the ink over the printing devices is effected through an ink distributing means comprising a brush 66 arranged on a 50 metal plate 67 operating between the printing

wheel and the bottom plate 12 and normally lying over the opening in the plate 12 through which the platens operate. This brush or distributor is secured to a depending portion 68 (see Figs. 7 to 9) on an arm 69 which projects from a rocking frame 70 mounted to turn on the shaft 14 of the printing wheel. A spring 71 anchored at 72 to the overhanging portion 2 of the base frame has its other end 73 secured to the swinging frame 70 and normally tends to hold the brush over that portion of the printing wheel at printing position. So that the ink distributor will be moved away from printing position when either of the levers or operators 37 and 44 are moved to move their respective platens, there is provided a slide 74 which through a headed screw 75 and slot 76 is guided on the overhanging portion 2 of the base frame at one end while the other end is pivotally connected at 77 at the swinging or oscillatory frame 70 to one side of the axis of turning of the latter. This slide 74 has two abutments 78 and 79, the former being adjacent the projection 80 on the shaft 38 and the latter being adjacent the projection 81 on the shaft 45 to provide two lost motion connections between the ink distributor and the two shafts 38 and 45. When the shaft 38 is operated, the projection 80 engages the abutments 78 and shifts the slide 74, and, when the shaft 45 is operated the projection 81 engages the abutment 79 and shifts the slide 74, so that both shafts 38 and 45 effect the movement of the ink distributor away from the printing point before the platens engage the printing wheel and against the action of the spring 71 which returns the slide 74 together with the ink distributor to normal position.

55 For feeding the work between the printing member and platen, there is employed a feeding device which, in this instance, comprises a plate 82 movable in the direction of the printing line and also transversely of the printing line. This feeding device has a clamping means associated therewith in the form of a clamp 83 pivoted at 84 to the plate and having a finger lever 85 on one side of the pivot and a downwardly deflected clamping portion 86 on the opposite side of the pivot cooperating with the top surface of the feeding plate 82, a spring 87 serving normally to hold the clamping portion 86 against the plate. The plate is further provided with two gages 88 and 89, the former extending longitudinally of the printing line and the latter extending transversely of the printing line and both serving to position one corner of the document to be printed on the feeding device.

60 In order to provide for the longitudinal and transverse movement of the feeding device, the latter has a guide member 90 projecting from one side thereof and, in this in-

70

75

80

85

90

95

100

105

110

115

120

125

130

stance, in the form of a sheet metal member of channel formation, the sides of the channel being turned downwardly. This guide member 90 is guided in ways in a carrier 91 mounted on the bed frame 1 and guided on said bed plate transversely of the printing line. In order that the guide member 90 may move easily within the guideway 91, a pair of rollers 91^a is provided on which the downwardly deflected side portions 90^a ride. A spring pressed roller 91^b situated in the side wall of the guideway urges the guide 90 against a pair of rollers 91^c in the opposite side wall. A cover plate 91^d, held to the guide way by screws 91^e, prevents the guide from shifting out of the guideway. This guiding is effected through a guide member 92 within the frame 1 and a shaft 93 which is journaled at its ends in the front and back members of the base frame 1 parallel with the guide 92, the carrier 91 having portions which slide upon the guide member 92 and the shaft 93. Movement of the carrier 91 may be effected by a rod 94 secured to the carrier on the outside of the frame 1, extending longitudinally of the shaft 3 and having its rear end turned upwardly at 95 whereby the rod 94 may be manipulated to shift the carrier and the work feeding device. The rod 94 may be guided in the guide bracket 96 and may be held in its adjusted position by a set screw 97 secured in the guide bracket 96. The purpose of this transverse adjustment of the work feeding device is to permit different lines of the check to be presented to the printing point of the machine.

The feeding device 82 is moved one distance with each printing operation of the outer set of short printing devices and a longer distance with each printing operation by the inner set of longer printing devices. This is effected, in this instance, through the shaft 93 which has a gear wheel 98 thereon frictionally secured to a sleeve 99 so as to turn in either direction on the sleeve under certain stresses, but to turn therewith under normal conditions as set forth in the Bullis patent herein mentioned. The sleeve is arranged to turn with the shaft 93 but is adapted to move longitudinally of the shaft and for this purpose is positioned between two abutments 100 and 101 formed on the carrier 91. The gear wheel 98 meshes with a rack on the guide 90 secured to the feeding device 82. The rack, in this instance, being formed by cutting slots in the bottom of the channel or the guide. It is apparent that rotation of the shaft 93 imparts rotation to the gear 98 and consequently a sliding movement to the guide 90. On the shaft 93 is arranged a ratchet wheel 102 and this ratchet wheel is so connected to the two platen operating mechanisms that the operation of either, to effect the printing operation, effects the turning of the shaft 93 through the ratchet 102.

When the lever 44 is operated to move the platen 32, a pawl 103 shifts the wheel 102. This is effected by pivoting the pawl 103 at 104 to a swinging arm 105 mounted to turn upon the shaft 93, this arm having connected to it at 106 a plunger 107 which, through a headed pin 108 and slot in which said pin operates, is guided on the link 49 to provide a positive connection for moving the plunger upwardly by the engagement of the pin with the end of the slot. A resilient connection between the link and the plunger 107 is provided comprising a spring 109 secured at its lower end to the link 49 and its upper end to the plunger 107. With the descent of the link 49, the latter pulls a plunger 107 downwardly through the spring 109 and shifts the swinging arm 105 to cause the ratchet 103 to ride over the ratchet wheel 102 without operating the latter. After the printing operation the link 49 rises and through the headed projection 108 lifts the plunger 107 and causes the ratchet wheel 102 to be shifted.

When the lever 37 is operated, the ratchet wheel 102 is shifted by a pawl 110 which is pivotally mounted at 111 on the end of a two armed lever 112, a spring 113 serving to hold the pawl toward the ratchet wheel 102. The lever 112 is pivoted at 114 to the base frame 1 and has a resilient connection with the operating mechanism for the lever 37. This connection, in this instance, embodies a spring 115 secured at one end to a platen lever 33 and the other end to the pawl carrying lever 115. An arm 116 projects downwardly from the platen carrying lever 33 and has a laterally projecting pin 117 which travels over a cam surface 118 on the lever 112 but which normally lies at the lower part of said cam. With the depression of the lever 37, the projection 117 rides upwardly on the cam 118 and positively depresses the forward end of the lever 112 while elevating the rear end, causing the pawl 110 to shift the ratchet 102. This shifting takes place before the platen 31 engages the printing member and thereafter the pin 117 rides on the cam 118 without effecting any further movement of the lever 112. When the lever 37 is released, the projection 117 rides to the lower portion of the cam 118 as the spring 115 pulls a lever 112 upwardly at its forward ends and downwardly at its rear end to cause the pawl 110 to ride over the teeth of the ratchet 102.

With the end in view of preventing the too free movement of the shaft 93, the latter carries the toothed wheel 119 with which a yielding holding member 120^a engages. This yielding holding member is in the form of a detent pivoted at 121 and pressed by a spring 122 toward the toothed wheel 119. It permits the turning of the toothed wheel by either the platen operating mechanism and yet holds the shaft and the toothed wheel 119 against accidental movement.

A stop mechanism is provided in connection with the feeding device, in order that the latter may be positioned to hold the check at desirable printing points. Some of such points are at the beginning of each line on the check and also at the beginning of the amount which is written in numbers adjacent the end of the amount line on the check. This is accomplished, in this instance, by a single stop bar or member 120 which is mounted in the channelled guide 90 adjacent one side wall of the channel and is guided by such guide wall through the provision of three inclined slots 121 in the side wall and pins 122 projecting from the stop bar and operating in the inclined slots. This stop bar is also guided by two projections 123 and 124 on the bottom of the channel cooperating with the other side of the bar 120. The projection 123 also serves as an anchor for the spring 125 which is secured at its other end to a projection 126 on the bar 120. Normally this spring holds the bar against the bottom of the channel or in its upper position with the pins 122 at the upper ends of the slots. This bar carries two stops 127 and 128 which are in the form of machine screws adapted to be fitted respectively into any one of the two longitudinally extending series of openings 129 and 130 in order that to provide for the adjustment of the stops 127 and 128. These stops are adapted to cooperate with an abutment 131 on the carrier 91 when the bar 120 is depressed or lowered. The stop 127 is employed for stopping the outward movement of the work feeding device 88 so that it holds the check at the beginning of the line in which is to be written the amount in numbers adjacent the end of the amount line, whereas, the stop 128 is employed when it is desired to stop the outward movement of the work feeding device at the beginning of the amount line or the line for the payee's name. Operation of the stop bar may be effected by a finger piece 132 projected upwardly from the stop bar adjacent a fixed finger piece 133 on the work feeding device 82. By pressing together the finger pieces 132 and 133, the bar 120 is moved against the action of the spring 125 to project the stops 127 and 128 so as to engage the abutment 131 on the carriage 91. As soon as the finger pieces are released, the spring moves the bar 120 upwardly and away from stop position.

While the machine can be employed for dating the check, it is preferred to use in connection therewith the dating mechanism and to this end, the work support 7 (see Figs. 19 to 23 inclusive) is provided to one side of the overhanging frame with a yielding platen 134 in the form of a rubber strip resting upon a depressed portion 135 of the feed plate 7 and having slits 136 at opposite ends through which the ends of the platen strip 134 are passed. Above the platen is mounted the date

printing mechanism comprising, in this instance, four rotary printing wheels 137, 138, 139 and 140 mounted upon a common shaft 141 supported in a swinging frame 142. Each printing wheel has at one side thereof a toothed wheel 143 with which a centering dog 144 on a shaft 145 engages. Each centering dog 144 is pressed toward its wheel 143 by a spring 146. Also mounted to turn on the shaft 145 are two arms or levers 147 each of which has a finger piece 148 arranged on the outside of the supporting member 142. On each arm 147 is pivoted a pawl 149 at 150 and with this pawl engages one arm 151 of a two armed spring mounted on the shaft 145 and abutting the supporting member at 151^a. The pawls 149 engage the toothed wheels 143 of the printing members 138 and 139 so that by pressing on either finger piece 148 one of the wheels 138 or 139 may be turned one step. The wheels 138 and 139 print the characters for the date of the month, whereas, the wheel 137 prints an abbreviation of the name of the month and the wheel 140 prints the last two characters in the year. The wheels 137 and 140 being required to be shifted only infrequently are moved by hand but the wheels 138 and 139 which require more frequent shifting are moved through the finger pieces 148. The carrier 142 for the printing members of the dating mechanism, is in this instance, pivoted at 152 to a bracket 153 which is adjustably secured by bolts 154 to the side of the upper frame member of the machine, in such a position that when the carrier 142 is swung downwardly on its pivot 152, the printing members will print on a check arranged on the platen 134.

With the end in view of inking the dating stamp, an inking device is provided, comprising, in this instance, a roller 155 journaled in the housing 156 which is pivoted at 157 to an arm 158 projected from the bracket 153 through a bifurcation in the printing carrier 142. This pivot 157 is eccentric to the pivot 152 of the housing 156 and a spring 159 acts on the housing 156 to hold the roller against the printing wheels and the pivoted carrier 142 against the cushion 160 on the arm 158. To effect the printing, pressure is applied to the carrier 142 to move the latter downwardly and this causes the roller 155 to roll over the characters of the printing wheels at printing point and thereafter shift out of the path of such characters so that when the characters strike the platen, the inking roller and its housing will lie to one side of the printing point. With the release of the carrier 142, the spring 159 presses upwardly on the housing 156 and, through the roller 155, presses the carrier 142 back to its normal position against the cushioned stop 160.

What I claim as my invention and desire to secure by Letters Patent is:

1. A printing machine comprising a print-

70

ing mechanism, a work feeding carriage movable in the direction of the printing line, a bar supported by said carriage, inclined guides on which the bar is movable, a stop carried by said bar for stopping the movement of the carriage, spring means acting on the bar to move it on the guides in order to carry the stop away from stopping position, a manually controlled means on the carriage connected with the bar to move the latter against the spring means in order to carry the stop to stopping position.

2. A printing machine comprising a printing mechanism, a work feeding carriage movable in the direction of the line of printing embodying a channelled member arranged in an inverted position, one side of the channel being provided with inclined guide slots, a bar arranged in the channel and having 15 projections operating in the slots, a stop carried by said bar for stopping the work feeding carriage at a certain point, a spring acting on said bar and arranged in said channel to hold the projections toward one end of the guide slots, and manually controlled means connected with the bar and mounted on the carriage for moving the bar against the action of the spring means toward the other ends of the slots.

3. The combination with a rotary printing member having an annular series of projections about its axis of rotation, of a pivotally mounted locking device for operation between said projections for locking the printing member in printing position, a member having a common pivot with the pivoted locking member, a spring interposed between said two copivoted members, a platen, and mechanism for operating the platen to cause it to cooperate with the printing member said mechanism having connection with the second of said copivoted members for moving the other of said copivoted member into position between any two of the projections on the printing member.

4. In a printing machine, the combination with a printing member having two sets of printing devices at different lengths, of two platens one for each set of printing devices, 50 two platen operating mechanisms, one for each platen, a work feeding device, a ratchet wheel connected with said work feeding device, two pawls cooperating with said ratchet wheel, one of which imparts greater movement to the ratchet wheel than the other, and two connections one between one pawl and a platen operating mechanism and the other between the other pawl and the other platen operating mechanism, whereby said pawls are moved by the two platen operating mechanisms.

5. The combination with a printing member, a movable platen for cooperating with the printing member, a work feeding device, a ratchet wheel connected to the work feeding

device, a swinging member mounted to turn about the axis of rotation of said ratchet, and a pawl carried by the swinging member and cooperating with the ratchet wheel, of operating mechanism for the platen, and a member guided on said operating mechanism and having resilient connection therewith, and also pivotally connected to the swinging member so that when the platen operating mechanism is moved in one direction the swinging member will be moved to carry the pawl over the ratchet wheel and when the platen operating mechanism is moved in the other direction the swinging member will be moved to move the ratchet wheel through the pawl.

6. The combination with a printing member and a platen movable to cooperate therewith, of a work feeding device for moving the work between the platen and printing member, a ratchet wheel connected with the work feeding device, mechanism for moving the platen toward and from the printing member having a swinging projection, a lever having a resilient connection with said mechanism and a cam portion engaged by said swinging projection, and a pawl carried by said lever and cooperating with the ratchet wheel.

7. The combination with a printing member and a platen for cooperating therewith, of a feeding device for moving the work between the platen and the printing member, a ratchet wheel connected with the feeding device to move the latter, mechanism for effecting relative movement between the platen and the printing member, a pawl for cooperating with the ratchet wheel, a member for operating said pawl having a resilient connection with the mechanism for effecting relative movement between the platen and the printing member, and also having a positive connection with said mechanism.

8. The combination with a printing member, and a platen for cooperating therewith, of a feeding device for moving the work between the platen and the printing member, a ratchet wheel connected with the feeding device to move the latter, mechanism for effecting relative movement between the platen and the printing member, a pawl for cooperating with the ratchet wheel, a member for operating said pawl having a resilient connection with the mechanism for effecting relative movement between the platen and the printing member, and also having a positive connection with said mechanism, the positive connection comprising a cam surface on the member and a part on the mechanism cooperating with said cam surface.

9. The combination with a printing member and a platen for cooperating therewith, of a feeding device for moving the work between the platen and the printing member, a ratchet wheel connected with the feeding

device to move the latter, mechanism for effecting relative movement between the platen and the printing member, a pawl for cooperating with the ratchet wheel, a member for operating said pawl having a resilient connection with the mechanism for effecting relative movement between the platen and the printing member, and also having a positive connection with said mechanism, the positive connection comprising a headed projection on the mechanism operating in a slot in the member.

10. A printing machine comprising a printing member, a platen for cooperating with the printing member, a double arm lever connected at one end to the platen to operate the latter and to cooperate with the printing member, a second double arm lever, a link connecting the two double arm levers, a rock shaft having a link connecting with the last mentioned double arm lever, cooperating portions on the last mentioned double arm lever and the rock shaft for limiting the movement of the double arm lever in one direction.

11. The combination with a printing wheel having a surrounding series of locking notches, of a centering wheel arranged to cooperate with said notches, a lever supporting said centering wheel at one end thereof, a spring acting on said lever to hold the centering wheel in engagement with the walls of the notches, and a guide cooperating with said lever adjacent the centering wheel.
